UNITED STATES PATENT OFFICE.

THOMAS P. HALPIN, OF CHICAGO, ILLINOIS.

TEMPORARY BINDER.

No. 802,101.

Specification of Letters Patent.

Patented Oct. 17, 1905.

Application filed January 16, 1905. Serial No. 241,309.

To all whom it may concern:

Be it known that I, THOMAS P. HALPIN, a citizen of the United States, residing at Chicago, in the county of Cook and State of Illinois, have invented certain new and useful Improvements in Temporary Binders, of which the following is a specification.

This invention relates to temporary binders of that general type adapted to receive and hold loose leaves in book form and of such construction that the leaves in any number can be readily removed or inserted at will.

Among the salient objects of the invention are to provide a temporary binder capable of expansion and contraction by means of sectional binder-posts and of such construction that the ends of the binder-posts do not project beyond the outer surface of the binder members, but are obscured therein, and to provide in a temporary binder a new and improved mechanism for locking the adjustable binder member in adjusted position upon the posts.

The invention will be readily understood from the following description, reference being had to the accompanying drawings, in which—

Figure 1 is a rear view of a binder embodying the present invention. Fig. 2 is a sectional view through the binder, showing the operating mechanism. Fig. 3 is a fragmentary sectional view taken on line 3 3 of Fig. 1. Fig. 4 is a similar view taken on line 4 4. Fig. 5 is an inside face view of the upper binder member. Fig. 6 is an inside face view of the lower binder member.

Referring to the drawings, 7 and 8 designate, respectively, upper and lower binder members, which, as shown, are of substantial thickness. These binder members are preferably made of wood, though it is obvious that they might be made of other material and that they need not be made solid.

9 designates a metal strip mounted upon the inner face of the lower binder member 8 and carrying two binder-posts 10 and 11, said posts being of the sectional type and secured rigidly to said strip. The binder member 7 is provided at its ends with openings 12 and 13, adapted to receive the ends of said binder-posts, said openings being closed at the upper side of the binder member by a couple of metal plates 14 15, mounted thereupon and which constitute stops to prevent the ends of the binder-posts from passing through the binder member 7.

Mounted upon the inner face of the binder member 7 is a spring-metal plate 16, having therethrough the openings 17 18, adapted to pass over the binder-posts as they enter the openings in the binder member, said plate being slotted throughout the distance between said openings and the middle portions thereof sprung apart, so that they normally tend to expand the openings 17 18 in such manner that the posts pass freely therethrough. In order to clamp said plate to the binder-posts, said plate is provided with a couple of lugs or ears 19 20, mounted on opposite sides of the slot therein and connected by a key-screw 21, by means of which the two portions of said plate can be positively drawn toward each other for the purpose of clamping the plate to the binder-posts or released to permit them to move to their normal position, which releases the posts and permits the binder member 7 to move upon the posts a distance corresponding to the depth of the openings 12 13, which is sufficient to permit the binder member 7 to be pressed downwardly upon the loose leaves in the binder and securely locked in place by means of the locking-plate 16. The key-receiving end of the screw 21 projects through an opening in the rear edge of the binder member, as clearly shown in Figs. 1 and 4.

Each of the binder members 7 8 is preferably covered, as with leather or canvas, (designated 22,) the edges of which project forwardly, as at 23, Figs. 3 and 4, to receive the back or cover members 24 25. (Shown in fragment in Figs. 3, 4.)

It will be seen from the construction described that a binder is provided the outer surfaces of which are left smooth and uninterrupted by binder-posts projecting through the binder members thereof, that the posts are obscured when the leaves are in place, and that the structure as a whole is neat in appearance and convenient to operate.

It is obvious that alterations and modifications in the details of construction and arrangement might be made without departing from the spirit of the invention, and I do not, therefore, limit the invention to the details here shown except in so far as they are made the subject-matter of specific claims.

I claim as my invention—

1. A temporary binder comprising a pair of binder members, one of which is provided with straight sectional binder-posts, and the other of which is made of substantial thickness

and provided with transverse sockets telescopically engaging said posts and of a depth approximating the length of the sections of the latter, and mechanism for locking said binder members in adjusted position upon said posts, substantially as described.

2. In a temporary binder, a pair of binder members, one of which is provided with binder posts of uniform size and the other of which is provided with a self-contained socket for each post, into which said posts telescope adjustably, a locking-plate upon the face of said latter binder member and provided with expandible post-receiving apertures registering with the open ends of said sockets, and means for positively expanding and contracting said apertures to lock said binder member upon the ends of said posts, substantially as described.

3. A temporary binder comprising in combination a binder member provided with straight binder-posts secured thereto and made in sections, a second binder member provided with self-contained sockets adapted to receive said posts telescopically, a locking-plate mounted upon said latter binder member and provided with post-receiving apertures registering with said sockets and slotted longitudinally between said apertures, and a screw arranged transversely of said plate and having threaded engagement with each portion thereof, whereby to positively expand or contract said apertures, substantially as described.

THOMAS P. HALPIN.
